Benjamin Hinckley.
Letters Patent

The Schedule referred to in these Letters Patent and making part of the same containing a description in the words of the said Benjamin Hinckley, himself, of his improvement in the washing machine.

This Machine may be worked in an oblong square box or tub, or in a common wash tub of sufficient width and to contain it. The construction of this machine commences with two curved pieces of wood which are twenty seven inches long, two and a half inches wide, and ^{inch} a half thick. These are placed about eleven inches apart, with the concave, upward. Small perforations say one fourth of an inch - and a half deep, are made in the above described curved pieces half an inch below the upper edges. These perforations which are ten in number are an inch and one fourth from each other, commencing at about three inches from one end and extending towards the other end twelve inches and a half, and this space between the curved side pieces is occupied by ten rollers which are eleven inches long and one inch thick, the quidgums of which are in the above mentioned perforations.

The quidgums may be made of iron, steel, or other kind of hard metal, and of such size as to work freely in the perforations which receive them. Two rounds of these rounds of the rollers are placed one before the first, and the other beyond the last of the ten rollers, leaving a space of one fourth of an inch between the rounds, and the roll. The ends of these rounds pass thro' the side pieces in suitable perforations or notches, and being secured by suitable pins, they connect and firmly fix the side pieces in their position. Immediately beyond the ten of rollers, and on the outward sides of the curved side pieces ^{upright pieces} of board are erected. These pieces are thirty three inches high, three and half inches wide at the lower ends, and two and half inches wide at the upper ends. These are secured in their places by fastening the lower ends in the side pieces by a dovetail. The upright pieces do not stand perfectly erect, but incline towards the rollers so that a line dropped from the top, will fall directly in the depth or centre of the curve. On the upper ends of the upright pieces are perforations, or mortises, extending from the upper ends, downward six inches. The tops of these mortises or sockets are open and the bottoms are semicircular and serve as a rest for the tub. The tub is an oblong square frame with twenty seven inches long and

about eleven inches wide. This consists of two side pieces which are two inches wide and three fourths of an inch thick, connected at top and bottom by cross pieces, that are one inch and a half square, and the ends of the upper cross pieces which extend outwards six inches and a half from the side pieces are filled to work in the above described sockets in the machine of guigeons. The construction of the rubber is completed by the addition of another piece of frame work, the side pieces of which are only eleven inches long, and of the same width and thickness of the others, and the lower ends are connected by a cross piece of the same construction of that which connects the lower ends of the other side pieces. These two pieces are connected into one by placing them together so that the two bottom pieces shall exactly correspond with each other, and they are secured in this position by scraping or sawing the upper ends of the latter side pieces firmly to the others. This piece of the machine is filled to operate as a sort of hand to grasp and hold the linen or other clothes designed to be washed. By cutting off the side pieces of the last described part of the rubber at about three inches from the upper ends, and affixing suitable hinges at the same places, so as to form joints. The two bottom pieces are made to lie open by means of slight steel springs which are placed between the side pieces of the two parts of the rubber. By dropping the guigeons of the upper and pieces of the rubber into the sockets of the upper ends of the upright pieces the rubber has to proper place in the machine. To facilitate the operation of the rubber it is caused from the rolling by two spiral springs which are secured in their proper place by blocks; that is to say, two inches wide, and one inch and a fourth thick. These blocks are perforated thro' from left to bottom with a half inch auger or bit, and one bit is secured on the outside of each of the upright pieces about three inches below the lower part of the blocks, and pins are filled to work in the perforations made in the blocks. These pins are about twelve inches long, the heads of the pins are three inches long two inches wide and one inch thick. On the top of the pins is a wire filled to receive the guigeons which extend outward from the upright pieces sufficiently to rest on the curved end of the pins. The aforementioned spiral springs enclose the lower part of the pins, and occupy a space of six inches between the upper ends of the perforated blocks, and the upper shoulder of the lower part of the head of the pins. A piece of lining is inserted under the aforementioned line of rolling, commencing at the end of the side pieces where the rolling commences, and extends about seven inches. The lining must be one inch

below the rollers that they may not be retarded in their motion. To operate this machine it is placed in the tub in an inclined position, one end of the curved side pieces resting on the bottom of the tub and the other end on the sides of the tub. The clothes are prepared as they usually are for washing by hand on a common wash board, and being thus prepared they are deposited in the tub together with the warm water. The person performing the labour places one or more pieces of linen or other clothes within the grasp of the rubber, and placing the hands upon the lower crook pieces of the rubber, by a circular motion the process of cleansing the clothes is effected with ease and despatch. All the rollers and rubber of various descriptions have been turned into machines constructed for the purpose of cleansing or washing clothes, yet I pledge that the foregoing describes a new arrangement and construction of the parts, constituting a new conformation and producing the effect by a mode of operation entirely new, and therefore claim it as my own invention.

The size of the machine may be varied so as to be adapted to any tub.
